UNITED STATES PATENT OFFICE.

EDWARD AMBROSE, OF TROY, NEW YORK, ASSIGNOR TO ISAAC A. SHEPPARD & CO., OF PHILADELPHIA, PENNSYLVANIA.

DESIGN FOR A HEATING-STOVE.

SPECIFICATION forming part of Design No. 25,811, dated July 21, 1896.
Application filed April 17, 1896. Serial No. 588,044. Term of patent 14 years.

To all whom it may concern:

Be it known that I, EDWARD AMBROSE, a citizen of the United States, and a resident of Troy, Rensselaer county, New York, have 5 invented a certain new and useful Design for a Heating-Stove, of which the following is a specification.

My design for a heating-stove is fully illustrated in the accompanying drawing, which 10 represents the stove in perspective.

The essential features of the design are the quadrangular base, which supports the body, the ornamented columns at the corners of the body, and the doors and illuminated panels. 15 The base A has an ornamented band a of interlaced scrolls, and the apron of this base-section, as well as the feet, have scroll ornamentation thereon. Each apron has a fan-like center a' , from each side of which extends a flaming scroll, and extending down each foot are elongated flame-like ribs.

The fire-pot section B is ornamented in keeping with the base of the stove and the ash-pit door b has leaf-like scrolls inclosing 25 the damper-section, which is pebbled, as shown.

The body-section B of the stove has columns d , and on each column is an ornamental cap in keeping with the ornaments of the 30 legs of the stove, and each column has transverse ribs some distance from the bottom, and on the upper and lower portions of the columns are leaf-like scrolls.

The two doors d' d'' are barred, the fire-door 35 d' having also cross-bars, and extending from

the hinge side of each door toward the handle are ornamental scrolls.

The upper portion of the body is curved outward, and in the curved portion is a central conventional design, on each side of which 40 is a leaf-like scroll.

The dome of the stove is ornamented by scrollwork in keeping with the design of the body.

The foot-rests e at each side of the stove 45 have scrolls thereon.

I claim—

1. The design for a heating-stove as herein described and as shown in the accompanying drawing.

2. In a design for a heating-stove the body as herein described and as shown in the accompanying drawing.

3. In a design for a heating-stove the base as herein described and as shown in the accompanying drawing. 55

4. In a design for a heating-stove the ash-pit door as herein described and as shown in the accompanying drawing.

5. In a design for a heating-stove the fire-door as herein described and as shown in the accompanying drawing. 60

In testimony whereof I have signed my name to this specification in the presence of two subscribing witnesses.

EDWARD AMBROSE.
